MACHINE FOR EDGING AND FORMING
 Walter Rutten, deceased, late of Plainfield, Ill., by Marion
 Rutten, Lester Quinn, and The Northern Trust Com-
 pany, executors, Plainfield, Ill.
 Filed Oct. 15, 1958, Ser. No. 767,350
 9 Claims. (Cl. 153—2)

This invention relates to improvements in a sheet forming and bending machine, and more particularly to machines for cutting, forming and edging metal sheets.

The principal object of this invention is to provide an improvement in sheet forming and bending machine wherein sheets of different lengths may be processed without major changes in machine set-up, and without the use of extra parts.

Another object of the invention is to provide an automatic pusher mechanism for moving a sheet into final stage operation.

A further object of the invention is to provide improved means associated with a machine of the type described whereby the sheet metal units which have been edged and formed may be given a final arcuate bend to a desired radius.

A further object of the invention is to provide a machine of the type described which in addition to the usual edging and grooving that has been done in the sheets in the past, also adds a stress neutralizing rib where required in the final arcuate bending of the sheet to a desired radius.

A further object of the invention is to provide improved drive mechanism in an apparatus of the class described whereby a work carrying table may be driven forward at a desired rate of speed throughout various operations of the machine, and then automatically reversed to return the work supporting carriage to a starting position.

This application is directed to improvements in a machine of the same type shown and described in the previous Walter Rutten Patent No. 2,339,355, issued January 18, 1944, present application otherwise having similar objects as set forth in said patent.

The above objects and advantages will be more apparent from the following description wherein reference is had to the accompanying drawings upon which like reference characters refer to like parts throughout the specification.

In the drawings:

FIG. 1 is a perspective view of a sheet metal blank which is to be trimmed to a desired size and then pre-formed with certain ribs and edge bends, after which the same is bent to a desired radius so that a plurality of the same when connected together at their edges, form a semi-spherical or dome-shaped roof;

FIG. 2 is a similar perspective view illustrating the first step in the process, which is the stamping of a bolt hole through the sheet adjacent its top or narrow end;

FIG. 3 is a similar perspective view illustrating the second step in the process, which is the forming of a medial rib longitudinally through the sheet;

FIG. 4 is a perspective view illustrating the third step of the process, which is the trimming of the longitudinal edges of the sheet so that the unit will be of a desired size;

FIG. 5 is a similar perspective view of the unit shown with the bolt hole, the middle longitudinal rib, and with the edge bends which have been formed in the same;

FIG. 6 is a perspective of the completed unit, showing the same bent to a radius so that a plurality of the units when connected together will form a semi-spherical enclosure;

FIG. 7 is an enlarged cross-sectional view through the unit taken generally on the line 7—7 of FIG. 6;

FIGS. 8, 8-A, 8-B, 8-C, and 8-D, when assembled to-

2

gether on the dot-dash separation lines, constitute a plan view of the entire machine, FIG. 8 being a plan view of the front end of the machine and starting platform, with a portion of the same broken away;

FIG. 8-A is a plan section of the portion of the machine directly forward therefrom and shows the sheet blank supporting rails;

FIG. 8-B is a plan view of the portion of the machine forward therefrom and shows, among other things, the edge cutting heads and edge rib forming heads;

FIG. 8-C is a plan view of the machine directly forward therefrom, showing, among other things, the pusher bar for starting or moving the sheet or unit forward into the curve bending rolls;

FIG. 8-D is a plan view of the portion of the machine directly forward therefrom, showing among other things, the mechanism for forming the sheet to a desired radius;

FIG. 80 is a vertical sectional view taken on the lines 80—80 of FIG. 8;

FIG. 80-A is a vertical sectional view taken on the lines 80a—80a of FIG. 8-A;

FIG. 80-B is a vertical sectional view taken on the line 80b—80b of 8-B;

FIG. 80-C is a vertical sectional view taken on the line 80c—80c of FIG. 8-C;

FIG. 80-D is a vertical sectional view taken on the line 80d—80d of FIG. 8-D;

FIG. 9 is a fragmentary vertical sectional view taken generally on the line 9—9 of FIG. 8, showing the hand operated guide and punch mechanism for making the bolt hole in the top end of the sheet;

FIG. 10 is a fragmentary horizontal sectional view thereof taken generally on the line 10—10 of FIG. 9;

FIG. 11 is a fragmentary vertical sectional view thereof taken on the line 11—11 of FIG. 9;

FIG. 12 is a vertical sectional view through the groove aligning and sheet guiding rollers, taken generally on the line 12—12 of FIG. 8;

FIG. 13 is a fragmentary horizontal sectional view taken on line 13—13 of FIG. 12;

FIG. 14 is an enlarged cross-sectional view through the central groove forming rollers and associated parts with the drive shafts therefor foreshortened, and is taken generally on the line 14—14 of FIG. 8;

FIG. 15 is a fragmentary transverse sectional view taken on the line 15—15 of FIG. 14;

FIGS. 16, 16-A, 16-B, 16-C and 16-D are fragmentary views showing the top and bottom forming rollers shown in FIG. 8 and the progressive steps through which the metal of the sheet is bent to form the middle groove therein;

FIG. 17 is a vertical sectional view through the temporary sheet support rails and associated mechanism, taken generally on the line 17—17 of FIG. 8;

FIG. 18 is a transverse sectional view taken on the line 18—18 of FIG. 17, showing the temporary sheet support and associated parts;

FIG. 19 is a plan view of the movable platform which consists of the front and back sections and the intermediate section which supports the saddle upon which the sheet is carried;

FIG. 20 is a side elevational view thereof including the endless chain that is attached thereto for reciprocating the same back and forth, the chain and its sprockets being shown generally diagrammatically;

FIG. 21 is a side elevational view of one of the edge rib forming heads with portions of the same broken into cross-section to more clearly show other portions thereof;

FIG. 21-A is a detailed vertical sectional view on line 21a—21a of FIG. 21;

FIG. 22 is a vertical sectional view through the drive

for the same, taken generally on the line 22—22 of FIG. 21;

FIG. 23 is a fragmentary plan view of one of the edge rib forming heads shown in FIG. 8-B;

FIG. 24 is an enlarged fragmentary sectional view showing the first set of the top and bottom rollers shown in FIG. 8-B, being the edge cutting rollers both to the right and to the left of the sheet that is going through the machine;

FIGS. 24-A, 24-B, 24-C, 24-D, 24-E, 24-F, 24-G, 24-H and 24-I are similar fragmentary sectional views showing the progressive right and left forming rollers and the progressive steps in the forming of the right and left edges of the sheet to the cross-sectional structure shown in FIG. 7;

FIG. 25 is a horizontal sectional view taken generally on the line 25—25 of FIG. 8-C;

FIG. 26 is a transverse sectional view of the pusher mechanism shown in FIG. 8-C, and is taken generally on the line 26—26 of FIG. 8-C;

FIG. 27 is a similar sectional view of the pusher mechanism taken on the line 27—27 of FIG. 8-C;

FIG. 28 is a back elevational view of the pusher fingers and carrier shown upon its support rails;

FIG. 29 is a plan view thereof;

FIG. 30 is an enlarged transverse sectional view through the frame of the machine and a portion of the movable carriage, taken generally on the line 30—30 of FIG. 20;

FIG. 31 is a fragmentary vertical sectional view showing how the drive chain is connected to the movable platform, taken generally on the line 31—31 of FIG. 30;

FIG. 32 is a fragmentary vertical sectional view taken on the line 32—32 of FIG. 8-D, showing the central curving roll at the sheet curving or arcing station;

FIG. 33 is a perspective view of the medial guide shoe that is provided at this station;

FIG. 34 is a fragmentary vertical sectional view of the central guide roll and shim adjustment for one of the radius to which the sheets are curved and is taken on line 34—34 of FIG. 32;

FIG. 35 is an enlarged fragmentary plan view of the parts generally shown in FIG. 32;

FIG. 36 is a fragmentary vertical sectional view through the top and bottom head rollers, showing the manner in which the stress equalizing ribs are formed, and taken on the line 36—36 of FIG. 35;

FIG. 37 is a fragmentary vertical sectional view of one of the radius forming heads and its adjusting mechanism, and is taken generally on the line 37—37 of FIG. 35;

FIG. 38 is a fragmentary sectional view through the shim adjusting means for the guide roller shaft taken on the line 38—38 of FIG. 37;

FIG. 39 is a generally diagrammatic side elevational view of the machine and the drive therefor;

FIG. 40 is a diagrammatic vertical sectional view taken on the line 40—40 of FIG. 39; and

FIG. 41 is a similar diagrammatic vertical sectional view taken on the line 41—41 of FIG. 39.

The method and apparatus illustrated will be described with particular reference to making sector-shaped roof sheets for silos, of the general type shown and described in U.S. Patent No. 2,112,348, issued to Peter Ruttan on March 29, 1938, although of course it will be understood that the machine and the method are not limited to the particular product above mentioned and the wide and varied latitude in which the same may be used will be more apparent as the description progresses.

In forming a roof sector of the type above described and as shown in FIGS. 1 to 7 of the drawings, a blank of sheet metal 10 is provided of the desired thickness or gauge for the purpose required. The blank 10 may be shaped similar to the finished product and may have the tapered edge walls 12 and 14, the reduced front end 16, and the back end 18.

The first step in the method employed is to punch a bolt hole 19 in the sheet at a point to one side of the center line thereof and adjacent the upper or front end 16 of the sheet. The next step in the method is to provide a medial groove 20 in the blank 10 along the center line of the same so that the blank may fit upon the island or saddle that is to carry it through the balance of the operations, and also to provide a reinforcing rib in the sheet medially thereof. The next step in the process is illustrated in FIG. 4. This consists of trimming the edges 12 and 14 and cutting off the portions 12a and 14a to bring the size of the blank to absolutely accurate dimensions and symmetrical upon both sides of the center line of the same.

The next step consists in making the edge or ridge formations 22 and 24 in the edges of the blank after the same have been trimmed to the desired size. The last step in the process consists in bending the entire blank 12 to the arcuate shape shown in FIG. 6 and with the cross-section shown in FIG. 7, so that when a plurality of the same are connected together they will generally form a semi-spherical roof or enclosure unit which is adaptable to various uses such as that described in the aforementioned patent.

It can thus be seen that the method employed consists of the movement of a flat metal blank through appropriate mechanism for forming surface configurations in the same, cutting the edges to trim the sheet to a desired size, bending the edges in a desired manner for making interlocking connection with other similar sheets, and then bending the entire unit into a desired shape. In the disclosure this is shown as arcuate, although it will be understood that the invention contemplates bending to other desirable shapes.

In FIG. 8 a starting platform 26 is shown upon which the sheet metal blanks may be placed with the forward edge 16 of the blank 10 resting against the flat edges 30 and 32 of a pair of stop pins 34 and 36. The edge 12 rests against a stationary pin 13 on the table 26 which is also formed with a ledge 26a along one side thereof parallel with the first set of forming rollers.

The guide pins 34 and 36 and a punch 40 for punching the bolt hole 19 in the sheet may be carried by a bracket 42 above a cross-bar 44 which extends between the sides of the machine. A hold-down assembly 41 having a spring loaded plunger is provided for molding the sheet during hole punching operation. The bracket 42 has an arm 46 extending upwardly therefrom carrying a pin 48 to connect the same with a handle member 50 that is connected by a link 52 to a pivot 54 on the cross-bar 44. The handle 50 is normally urged upwardly by the spring 56 (FIG. 8) so that in normal operation the sheet can be moved forward without abutting the punch 40 and stop pins 34 and 36. However, when a sheet is ready to go through the machine, the handle is pulled down and the punch is lowered so that the sheet abuts the stop fingers, and downward pressure on the lever will then transmit the pressure through the bracket 42 to the punch 40 and punch the opening 19 in the sheet, after which the handle 50 is raised and the sheet may be manually lifted and moved forward to go through the medial groove forming rollers 60 (FIGS. 16 to 16-D). The bracket 42 also carries a yieldingly mounted vertical brace member 41 which holds the forward edge of the sheet down against the stop pins 34 and 36 during a punching operation.

The medial groove forming rollers 60 may consist of upper and lower rollers 60a and 60b with complementary progressive groove forming faces thereon. As shown in FIG. 16, the rollers form the three-sided groove formation 61; in FIG. 16-A the formation 63; in FIG. 16-B the further formation 65; in FIG. 16-C the further formation 67, and in FIG. 16-D the completed groove 20 (as shown in FIG. 3, etc.) is formed in the sheet 10.

As best shown in FIGS. 14 and 15, each set of rollers

60a and 60b are mounted upon cross-shafts 62 and 64 respectively, 62 being the upper shafts and 64 the lower shafts. The lower shafts 64 are mounted in suitable fixed bearings 66 in the horizontal frame members 68 of the machine, the shaft 64 at one end having a face gear 70 meshing with a face gear 72 on the end of the shaft 62, and the shaft 64 at the other end having a sprocket 74 geared to a chain 76 for a drive for the same.

The upper shafts 62 are mounted in spring-pressed movable bearings 78, the bearings being mounted for yielding vertical movement, the spring members 80 normally holding the same in working position. As best seen in FIG. 8, the drive from chain 76 may go to a sprocket 82 on the next shaft 64, which in turn is connected with the next shaft 64 by a chain and sprocket, the shafts 64 all being connected together so that a drive to one will communicate the drive to all the others, and each of the shafts 64 will in turn communicate a drive to its cooperating shaft 62 by means of the face gears 70 and 72.

By means of the forming rollers above described, the sheet 10 is thus moving forward with its back corner in the channel 26a, and the medial groove 20, previously described, is thus being formed in the sheet. As the forward edge of the sheet moves forward from the last forming roll 60, the rib 20 is guided by a plurality of horizontally disposed rollers 84 mounted upon a plate 85 supported on a cross-bar 88 between the side horizontally disposed channel frame members 90 and 92. The rollers 84 are eccentrically mounted upon holding bolts 85 so that minute adjustment may be made to insure absolute accuracy in the alignment of the sheets. Thus the sheet with the medial groove formed therein is run forward by the rollers 60 upon the temporary sheet support rails prior to being fed into the edge forming head assembly shown in FIG. 8-B.

The temporary sheet support rails 94 and 96 may be mounted at their rear ends upon a rod 98 mounted in suitable bearings in the side frame members 68 at the forward edge of the support platform 69 adjacent the forming rolls 60. The rails 94 and 96 terminate at their forward ends in a downwardly depending portion 100 which has a flattened rearwardly extending foot 102 supported in a saddle 104 fastened to the top of lever 106. The levers 106 are fastened to a pivot shaft 108 and normally held in the position shown in FIG. 17 by a tension spring 110 attached to a lever 109 fastened to shaft 108. In the position shown in FIG. 17, the rails are supporting a blank or metal sheet 10 ready to be picked up and moved forward by the movable carriage or table 112. When the movable carriage 112 moves left (FIG. 17), its forward edge engages the levers 106 and rotates the same counterclockwise against the tension of spring 110 to permit further forward movement of carriage 112. The carriage moves in this direction until the section B (later to be described) of the carriage lies under the sheet 10, the back or wide end of B being near the rollers 84.

The movable carriage or table 112 may consist of three sections, A, B and C (FIGS. 19 and 20), suitably connected together at their adjoining edges. Each section may consist of a flat metal sheet or platform 114 (FIG. 30) which has cross-bars beneath the same at intervals of approximately twenty-four inches, and each section has a carriage therebeneath which consists of the angle members 116 at each side of the same carrying vertically disposed rollers 118, and a second set of angle members 120 carrying horizontally disposed rollers 122. The rollers 118 ride upon vertical rails 124 fastened inside the side frame members 90 and 92 throughout the length of the machine, and the horizontal rollers 122 ride against the inner vertical walls of these rails, thus assuring at all times a level horizontal travel as well as a guided lateral travel by the rollers 122.

The sections A, B and C of the movable carriage or table 112 carry upon their upper surface the cam track members 126a, 126b and 126c for guiding the movement of the edge forming rollers, as will presently be described.

5 The cam track members 126a on the table top 114 of section A are spaced apart and parallel as can be seen in FIG. 19, and the cam track member 126b on the section B of the carriage are formed to correspond to the shape to which the sheet is to be formed, and terminate at their forward ends in a connection with parallel tracks 126c on the platform C spaced close together.

The sheet carrying island 128 which is fastened on the portion B of the table 112 is of sufficient height above the table so that when the same is moved back and the table portion A rides below the temporary support rails 94 and 96 they will permit the island 128 to move below and pick up the blank 10 from the support rails 94 and 96 and move forward with the same through the edge cutting and forming rollers presently to be described.

10 15 20 25 Channel members 103, secured to the platform 114, serve as a guide means for the end of each foot 102 as the carriage moves thereunder. Hold-down rollers 130, supported on uprights secured to frames 90 and 92, as seen in FIG. 17, may be provided at intervals between the forming rollers 60 and the edge cutting and forming rollers, if desired. The island 128 (FIGS. 26, 27) may be generally triangular in shape, similar to the shape formed by the cam tracks 126b.

30 35 Referring now to FIG. 8-B, a plurality of forming head units 132 may be provided, and in the construction shown five of these heads will be mounted on the right side and five on the left side of the machine upon guide bars 138, the guide bars being mounted, for reciprocal motion toward and away from the center of the machine, as will be hereinafter more clearly described.

The Forming Heads

The forming head units 132 may be identical in construction, in their mode of operation and in the manner in which they are driven. Therefore in this disclosure only one set of heads will be described, it being understood that the others are similar except for the differences which will appear.

40 45 50 As shown in FIGS. 21, 21-A, 22 and 23, the forming heads 132 may include a base plate 134 which is pivotally connected by the screw member 136 at its forward end to a guide member 138, the screw member also fastening a roller 140 beneath the guide 138. The back end of the base plate 134 is provided with an arcuate slot 142 for receiving the screw member 144 for angular movement of the base plate on the guide 138.

55 60 65 Each of the heads has the guide 138 extending away from the center of the machine, the guide being controlled by additional horizontal rollers 146 mounted on top of the table side portions 148. Additional guide rollers 150, mounted to the table portions 148 in vertical position, hold down the parallel sided guides 138 so that as the forming heads move in and out according to the path of the cam tracks 126, the sets of forming heads will be moved apart and together generally in a straight line.

70 75 The forming heads 132 may contain in each unit two housings 152 which are duplicates, each housing consisting of the two halves 152a and 152b pivoted together at their back ends and held in the desired relationship by means of pairs of bolt members 154 screw-threaded at their lower ends into the lower housing portion 152b and holding a compression spring 156 against the shoulder 158 of the upper housing 152a. Each housing contains a stub shaft 160 having a forming roller 162 connected to its forward end. Each housing also has a face gear 164 therein keyed to its respective shaft, the gears 164 being in mesh.

The lower shaft 160 carries a sprocket 166 at its outer end, the sprocket being connected in driving relation by a chain drive 168. The lower shaft 160 of one of the

housing units 152 is connected by a universal joint 170 to a square drive shaft 172 whereby power is supplied for rotating both the upper and lower forming rollers 162 of both of the head units 132.

The head units are minutely adjusted upon the base 5 plate 134 by the set screws 174 on both sides of the shaft 160. Each of the heads 152 is also fastened by means of the bolt 176 and dovetail slide 178 for both back and forth and slight angular adjustment to the base plate 134. The slide 178 carries a horizontally disposed roller 180 10 at its forward end, the roller being spaced downwardly from the slide sufficiently so that it engages the inside edge of the cam track 126. In this way the forming head units 132 are held by the three rollers 180, 180 and 140 in engagement with the cam track 126, and as this track is 15 moved forward or back, separating or coming together, the head units will follow the movement of the same.

The drive for the forming rollers 162 as previously mentioned, is received through the shaft 172, which is a square shaft and which in its back and forth sliding movement engages a hollow shaft 182 fastened in suitable bearings 184 in a horizontally disposed bearing box 186 mounted on the table portion 148 for rotation in an opening 188 therein.

The hollow shaft 182 has a bevel gear 192 keyed thereto in mesh with a similar bevel gear 194 at the upper end of a shaft 196. The shaft 196, mounted in suitable vertical bearings 198, has a similar bevel gear 200 connected at its lower end, the gear 200 being in mesh with a drive bevel gear 202 fastened on the drive shaft 204. The drive shaft 204 is mounted in suitable bearings 206 in a housing 208 that is fastened by the shoulders 210 to one of the side frame members 90 or 92. Bolts 211 may be the fastening means.

The forming rollers 162 consist of upper and lower rollers with complementary configuration. The first set is the cutting rollers 162a and 162b which are formed to trim the edges of the blank 10 to the exact size and shape required, shearing off the waste strips 12a and 14a, as shown in FIG. 24. The balance of the figures, 24-A through 24-I, respectively, show forming rollers 162c and 162d with complementary engaging surface configuration of a shape so that in the finishing of the edges they will conform exactly in dimensions, angle and shape to the edges 22 and 24 shown in FIG. 7.

From the above description it can be seen that in the forming of the edge shapes, due to the spring members 156 the forming rollers 162 will normally be held together, but when a blank of sheet material passes between the same the upper roller is permitted against the spring tension to rise sufficiently to permit the thickness of the blank to pass between the same and be formed according to the contour of the rollers.

It will also be apparent that a construction of work head has been provided which carries two sets of forming rollers, each of which is individually guided by the cam track 126, and may be individually adjusted upon the base plate 134. With the construction shown and with a drive from the shaft 204 to each head unit 132, the speed of the work rollers in each unit will be the same.

The Pusher Mechanism

After the blank has been run through the forming heads heretofore described, the same being carried on the island 128, the blank will be in position for the final or curving operation of the sheet, and the island stops at the end of its forward movement and closes a switch 113a actuation of the pusher mechanism which sends the same into the curving rollers.

As shown in FIG. 8-C, and FIGS. 25 to 27, the movable platform 114 will stop with the portion B thereof and the platform or island 128 positioned below the pusher mechanism 220. This mechanism may include a pair of cross-braces 222 and 224 in the form of inverted

channels positioned at the upper ends of upright channel members 226 and 228. The frame members are also connected adjacent the upper ends by longitudinal bars 230 between the channels 222 and 224 and lower channels 232 between the uprights 226 and 228. Thus a rectangular framework is formed which may be movable as a unit, and in use the same is moved back and forth on top of the side frame members 90 and 92 of the machine, and is fastened in a desired location by suitable clamp members 236. This movement is necessary to compensate for the difference in the length of the various size blanks and islands which may be used in the machine.

The pusher unit may include a reversible air motor including a pivotally mounted air cylinder 240 supported below the cross-frame member 224 by a pair of support brackets 242. Compressed air for operating the piston therein in either direction is provided which is directed by a solenoid operated two-way air control valve 244 through the conduits 246 and 248 to the back and front ends of the cylinder respectively.

The cylinder is adapted to reciprocate a piston that has a piston rod 250 extending from the back end of the same, the piston rod 250 being fastened to a bracket 252 which has the side arms 254 extending outwardly therefrom. The arms 254 may be pivotally connected to a pair of sliding collars 256, the collars 256 each being guided on the rods 258 that are mounted in support brackets 260. The collars 256 each have a bar 262 extending forward therefrom, both bars being connected at their forward ends to a cross-bar 264. The cross-bar 264 extends outwardly from the center of the machine to a point adjacent each of the side edges of the same and has adjustable pusher fingers mounted thereon, the pusher finger assemblies 267 being shown in FIGS. 25 and 26 with the suspended fingers 268 against the back edges of the formed blank 10.

The pusher finger assemblies, as best shown in FIGS. 28 and 29, may include a bracket 270 that has a square opening therethrough and is slidably mounted on the cross-bar 264. It may be adjusted outwardly or inwardly as desired and fastened in place by a set screw 272. Each of the fingers 268 may be supported on a pivot set screw 274, the fingers having an upwardly extending neck portion 276 having a hook 278 for engaging on a knob 280 to hang in a perpendicular position.

Thus when a sheet 10 is moving forward under the pusher unit and with the cross-bar 264 carrying the finger assemblies moved back toward the rear of the machine, the outer edges of the blank will bear against the inner edges of the pusher fingers 268, swinging them about the pivot 274, as shown by the arrow in FIG. 28, until the back edge of the blank has been moved past the fingers, at which time by gravity they will swing back to a vertical position. The piston rod and cross-bar assemblies are shown in this end of their action. As the platform 114 reaches end of forward stroke, it closes the switch 113a, as hereinbefore described, whereupon the valve 244, which is in the circuit of switch 113a, will direct air so that the piston rod 250 will move forward,

bringing the bar 264 and pusher fingers to move the front end 16 of the blank 10 into the curving rollers. A hold-down roller 259 is mounted in a suitable bracket carried by the back end of the guide rods 258. The roller 259 normally rolls on top of the blank going through the machine. It should be borne in mind that the purpose of the pusher fingers is to move the sheet or blank 10 forward only enough so that the end is fed between the driving or pull rollers 300, which then take over and pull the entire sheet through the radius forming machine.

Switches 113b (FIG. 8-D) each of which are mounted upon an arm 349 of a door check mechanism 347, are of the normally open type, but as used are initially closed, and will open when the heads 326 move outwardly, as will be explained. A switch 113c, of the normally open type, but as used is initially closed, is opened as a sheet

leaves a set of radius forming rolls, also to be explained. The switches 113a, 113b, and 113c are in series, and when all are closed, the solenoid valve 244 is operated, whereby the pusher mechanism 220, will move the sheet forward into the bending rolls. When any of these switches is opened, the solenoid valve 244 will be operated to cause movement of the pusher mechanism 220 in the opposite direction.

The Radius Forming Station

The sheet 10, which is now finished except for forming it to the radius desired for the silo roof, now rests upon the movable platform or island 128, with the forward edge 16 of the sheet in a position being moved forward from the position shown in FIG. 8-D by the pusher fingers into engagement with the pull rollers 300 mounted on the shafts 302 which extend across the machine and are supported in suitable bearing supports 304 in the side frame on the horizontal frame members 90 and 92. A pair of cross-bars 306 and 308 connect the bearing supports 304 on the front of the same and have attached to the forward edge thereof and medially thereof of a guide shoe 310 which has a tapered finger 312 that engages the medial groove 20 of the sheet for guiding the same forward between the pull rollers 300. Additional guide shoes 314 are also fastened to the cross-bars 306 and 308 for guiding the tapered edges 12 and 14 through the radius forming rolls.

After the forward edge 16 of the sheet 10 has passed through the pull rolls 300, it engages three sets of rolls, the middle set of rolls 316, 318 and 320 engaging the middle groove 20, and the two sets of side rollers 322 and 324 engaging the side edges 12 and 14 respectively.

The two sets of side rollers 322 on each side are mounted in a forming head 326 similar to the forming heads 132, and are also mounted upon a base plate 328 similar to the base plate 134. Each of the plates 328 may be fastened on movable platforms 330, the platforms being rectangular in shape and being mounted for reciprocation upon a pair of horizontal cross-rods 331 which extend above the transverse frame channels 90 and 92 into a pair of support plates 333 parallel to and spaced from the horizontal frame members 90 and 92. The plates 333 are fastened to vertically disposed cross-bars 335 which confine the parallel edges of the platforms 330 therebetween, the first of which is fastened against the frame 304 for the pull rollers 300.

Each of the base plates 328 for the forming heads 326 is pivotally held on the platform 338 by a set screw 337 and is capable of limited arcuate turning thereon, having an outer slot 339 with a guide pin extending therethrough. A flat tapered plate 341 may be fastened on the platform 330 on one side of the base plate 328 to position the desired angle of the curving rollers 322 and 324. This plate normally holds the curving rollers in the position to follow the taper of the formed side edges 22 and 24 of the unit 10. However, since the lower or base end of the units 10 is frequently straight-away for about 12 or 15 inches rather than curved, guide shoes 343 fastened against the side plates 335 adjacent their ends swing the base plates 328 about their pivots 337 to follow the straightened edges of the units. This movement is against the compression spring 345, and on the return movement of the forming heads they of course return to the normal position shown in FIG. 8-D.

The heads 326 and the curve forming rollers 322 and 324 are of course swung apart as a tapered unit is moved through the same by the pull rollers 300. They are returned from this spaced-apart position by a door check mechanism 347, one fastened on each side of the horizontal frame members 90 and 92. Each door check may include an arm 349 pivotally connected to a second arm 351 that is pivotally connected by the pin 353 below the movable platform 330. These door checks are of the well known type that yield to outward movement

5

and then slowly bring the door or other object back to its normal position.

A drive similar to that for the forming heads previously described may include a shaft 342 connected at its forward end to each of the rollers 322, the same being in driving relation in opposite directions between face gears 344, the lower shaft 342 extending outwardly beyond the head 326 through an arm 346. It also carries a sprocket 348 and by means of a universal joint connects to a square shaft 352 that extends through a horizontally disposed bearing box 354 mounted on the outside of the cross-frame 333, the same being similar to the bearing box 186 mounted on the table portion 148 through which the drive for the forming heads is obtained.

35

40

45

50

55

60

65

70

75

The sprocket 348 is connected by a chain drive 356 to a similar sprocket 358 on the end of a drive shaft 360 connected to the side roller 324. A second arm 346a supports a housing 362 in which said shaft is journaled adjacent the roller 324, the housing 362 being mounted on a shim 364. It will be noted that the roller 324 is thus higher than the pull rollers 300, the roller 320 being higher than the pull rollers 300 so that as the sheet is moved forward over these rollers an arc or radius of a predetermined dimension is formed in the sheet.

In order to make the sheets into roof sectors for various sizes of silo roofs, as for example 12', 14', 16', 18' or 20' diameter silo roofs, different size shims 364 are provided for supporting the housing 362 on the rollers 324, and thus it is a simple matter to take the required size shim, lift the housing 362 up on the arms 346 and 346a and replace the shim 364. Each shim has a central opening 366 for mounting upon a pin 368 in a shim block 370, the block 370 being normally held in fixed position on the base plate 328 by angle members 372.

A similar arrangement is provided for correspondingly raising or lowering the medial roller 320. This roller is mounted in a bearing 374 which has a pair of side walls 376 that engage over a bar 378, the base of the bearing 374 resting upon a flat shim 380 of desired thickness on top of the block 378. For a difference in radius of the sheet, the bearing 374 and roller 320 are removed and a thicker or thinner shim may be substituted as required.

Thus it can be seen from the foregoing that a comparatively simple means has been arranged for easily and quickly changing the radius forming rolls of the machine to form the completed sheets into sectors of a different radius whenever desired.

The radius forming rollers 322 and 324 which engage the edges of the tapered sheet are moved outwardly, as previously described, as the sheet passes through the radius forming portion of the machine. The forming head 326 are guided outwardly by the cross-rods or guides 331 and moved outwardly by the ever expanding size of the sheet as it is traveling through and being curved.

After the sheet has been curved it comes to rest on the curved sheet support bed 382 supported at its upper end on the uprights 384 at the end of the machine, from whence it is removed by the workman in charge. As the sheet leaves the radius forming heads they are of course spread apart, supported on the guides 331, and are returned to their normal beginning position by the door check mechanism provided.

Driving Mechanism

Means for driving the entire machine will now be generally described. This mechanism may consist of a motor 400 which through a set of reduction gearings 402 drives the shaft 404, and by means of chain drives 406 drives the shafts 204, from whence a drive to the forming heads is obtained, as previously described.

One of the shafts 204 extends to the center groove forming station where a universal connection 205 is made to a stub shaft 207 into a gear box 209. A shaft 213 may extend from this gear box to drive the series

of chains 82 previously described, whereby the groove forming rollers 60 are all driven.

The shaft 213 also carries a sprocket 215 which drives a chain 217 that engages a sprocket 219 on a cross-shaft 221. The shaft 221 extends across the machine below the frame members 90 and 92 and engages a clutch 223. The shaft also carries a comparatively large face gear 225 which is constantly in mesh with a smaller face gear 227 mounted on a cross-shaft 229. The shaft 229 also carries a clutch 231 and there is a chain drive 10 connection between the shaft 229 extending down from the clutch 231 and the shaft 221 extending down from the clutch 223. The purpose of this arrangement is so that when the clutch handle 452, hereinafter described, is moved in one direction, the platform will be moved forward at a comparatively slow speed, and when the clutch handle is shifted the carriage will be brought back at a faster speed. In a neutral position there will be no drive either forward or back.

A clutch rod 450 for shifting the direction of the platform drive chain has a handle 451 located adjacent the edge forming roll section of the machine, and the operator can thus operate the chain drive for the movable platform 114 to stop the same, move it forward or move it back. The drive for this table may include an endless chain 452 (see FIGS. 20, 30 and 31), which is trained about sprockets 454 at the front end and 456 at the back end of the machine. This chain may be guided to travel in the chain tracks 460 and 462 supported on the cross-rails 17 of the horizontal frame of the machine, the chain being connected by a cross-bar 458 and bolt 464 to the movable platform 114 at a point adjacent the left end of the same, FIG. 20.

The drive for the radius forming station is obtained from a second motor 480 which has a chain drive 482 to the lower pull shaft 302. A chain drive 484 extends from a sprocket 483 on the end of shaft 302 to drive a horizontal cross-shaft 303. A bevelled gear on each end of shaft 303 drives a vertical shaft 303a in each of the gear housings 354, this drive connection being generally similar to the shaft 204 and related drive to the forming heads (see FIG. 22).

From the above and foregoing description it can be seen that the machine which has been described herein, while generally similar to that shown in the previous patent to the same inventor, has many improvements over the same; specifically, as now constructed and operated, the machine includes additional stations which have been found convenient in the operation of such a machine. These stations are the temporary sheet holding rails at the forward end of the center groove forming rollers which will prevent accidental mutilation or deforming of the sheets after they leave the center groove forming rolls and will hold the same in readiness until the operator is ready to send the movable platform and support island back to pick up the same. An outstanding feature of the temporary sheet supporting rails is that they allow sheets of different lengths to be fabricated without major change in machine setup. For example, in my prior patent, supra, change in sheet length required change in length of the equivalent carriage island.

The pusher means right beyond the forming heads has also been found highly advantageous in efficient operation in that when a sheet has been trimmed and the edges have been properly formed and it is ready for introduction into the radius curving heads, the sheet may sometime be slightly warped or bent so that it was previously necessary to hand feed at this stage. By means of the automatic pusher mechanism developed and the additional guide units such as the guide shoe 310 adjacent the feed rolls in the radius forming mechanism, the proper forward movement of each sheet is assured and the operator is only required to operate his clutch lever, whereupon the pusher mechanism will move forward,

and be returned to initial position, as the sheet is being bent by the curving rolls.

From the above description it will be apparent to those skilled in the art that the machine herein provided insures a simple continuous process of edging or cutting and forming a flat sheet into a desired size, shape and surface configuration. The improved construction of forming heads and their operation is also such that they operate with a maximum of efficiency and can be modified or changed with a minimum of effort. In the same manner, the use of the shim construction and arrangement in connection with the radius forming mechanism, assures accurate changes from one size to another when desired.

Although changes and modifications may be made in the exact details shown, what is desired to be protected by Letters Patent of the United States is:

1. In a straight line machine for fabricating tapered sheet metal blanks including a starting platform having guide means for a sheet metal blank thereon, a set of forming rollers forward of said platform for making a medial groove in said blank, a movable carriage, a saddle on said carriage for support of a sheet metal blank, cam tracks on said carriage, a set of edge cutting and forming rollers in advance of said platform, means for moving said carriage forward past the medial groove forming rollers and the edge cutting and forming rollers, and a radius forming mechanism in advance of said edge cutting and forming rollers for bending a tapered blank to a desired shape, the improvement consisting of a pusher mechanism for moving a blank into said radius forming mechanism, means for operation of said pusher mechanism, and switch means adapted to sequentially provide both forward and reverse movement of said pusher mechanism.

2. In a straight line machine for fabricating tapered sheet metal blanks including a starting platform having guide means for a sheet metal blank thereon, a set of forming rollers forward of said platform for making a medial groove in said blank, a movable carriage, a saddle on said carriage for support of a sheet metal blank, cam tracks on said carriage, a set of edge cutting and forming rollers in advance of said platform, means for moving said carriage forward past the medial groove forming rollers and the edge cutting and forming rollers, and a radius forming mechanism in advance of said edge cutting and forming rollers for bending a tapered blank to a desired shape, the improvement consisting of a pusher mechanism for moving a blank into said radius forming mechanism, means for operation of said pusher mechanism including a reversible air motor and a solenoid operated two-way air valve, and switch means adapted for operation of said valve to provide forward and reverse movement of said pusher mechanism.

3. In a straight line machine for fabricating tapered sheet metal blanks including a starting platform having guide means for a sheet metal blank thereon, a set of forming rollers forward of said platform for making a medial groove in said blank, a movable carriage, a saddle on said carriage for support of a sheet metal blank, cam tracks on said carriage, a set of edge cutting and forming rollers in advance of said platform, means for moving said carriage forward past the medial groove forming rollers and the edge cutting and forming rollers, and a radius forming mechanism in advance of said edge cutting and forming rollers for bending a tapered blank to a desired shape, the improvement consisting of a pusher mechanism for moving a blank into said radius forming mechanism, said pusher mechanism including a reversible air motor, a solenoid operated two-way air valve, and means movable by said air motor for engagement with the end of a blank, and switch means adapted for operation of said valve to provide forward and reverse movement of said pusher mechanism.

4. In a straight line machine for fabricating tapered

sheet metal blanks including a starting platform having guide means for a sheet metal blank thereon, a set of forming rollers forward of said platform for making a medial groove in said blank, a movable carriage, a saddle on said carriage for support of a sheet metal blank, cam tracks on said carriage, a set of edge cutting and forming rollers in advance of said platform, means for moving said carriage forward past the medial groove forming rollers and the edge cutting and forming rollers, and a radius forming mechanism in advance of said edge cutting and forming rollers for bending a tapered blank to a desired shape, the improvement consisting of a pusher mechanism for moving a blank into said radius forming mechanism, said pusher mechanism including a reversible air motor, a solenoid operated two-way air valve, and means movable by said air motor including swinging fingers which are spread apart by a blank as it moves forward and then swing back by gravity behind the back edge of said blank to engage the same, and switch means for control of said valve, said switch means including a plurality of switches in series, one of said switches being closable upon engagement by said carriage to initiate forward movement of said pusher mechanism.

5. In a straight line machine for fabricating tapered sheet metal blanks including a starting platform having guide means for a sheet metal blank thereon, a set of forming rollers forward of said platform for making a medial groove in said blank, a movable carriage, a saddle on said carriage for support of a sheet metal blank, cam tracks on said carriage, a set of edge cutting and forming rollers in advance of said platform, means for moving said carriage forward past the medial groove forming rollers and the edge cutting and forming rollers, and a radius forming mechanism in advance of said edge cutting and forming rollers for bending a tapered blank to a desired shape, the improvement consisting of a pusher mechanism for moving a blank into said radius forming mechanism, said pusher mechanism including a reversible air motor, a solenoid operated two-way air valve, and means movable by said air motor including swinging fingers which are spread apart by a blank as it moves forward and then swing back by gravity behind the back edge of said blank to engage the same, and switch means for control of said valve, said switch means including a plurality of switches in series, one of said switches being closable upon engagement by said carriage to initiate forward movement of said pusher mechanism, said switches being further arranged so that upon opening of any one thereof, the solenoid valve will function to cause movement of said pusher mechanism in a direction away from said radius forming mechanism.

6. In a straight line machine for fabricating tapered sheet metal blanks including a starting platform having guide means for a sheet metal blank thereon, a set of forming rollers forward of said platform for making a medial groove in said blank, a movable carriage, a saddle on said carriage for support of a sheet metal blank, cam tracks on said carriage, a set of edge cutting and forming rollers in advance of said platform, means for moving said carriage forward past the medial groove forming rollers and the edge cutting and forming rollers, and a radius forming mechanism in advance of said edge cutting and forming rollers for bending a tapered blank to a desired shape, the improvement consisting of a pusher mechanism for moving a blank into said radius forming mechanism, said pusher mechanism including a reversible air motor, a solenoid operated two-way air valve, means movable by said air motor including swinging fingers which are spread apart by a blank as it moves forward and then swing back by gravity behind the back edge of said blank to engage the same, and switch means for control of said valve, said switch means including a plurality of switches in series, one of said switches being closable upon engagement by said carriage to initiate forward movement of said pusher mechanism, said switches

being further arranged so that upon opening of any one thereof, the solenoid valve will function to cause movement of said pusher mechanism in a direction away from said radius forming mechanism, said switches being of the normally open type and being arranged so that all but the one closable upon engagement by the carriage are in closed condition prior to movement of the blank through the radius forming mechanism, and are moved to open condition as the blank passes through the radius forming mechanism.

7. In a straight line machine for fabricating tapered sheet metal blanks including a starting platform having guide means for a sheet metal blank thereon, a set of forming rollers forward of said platform for making a medial groove in said blank, a movable carriage, a saddle on said carriage for support of a sheet metal blank, cam tracks on said carriage, a set of edge cutting and forming rollers in advance of said platform, means for moving said carriage forward past the medial groove forming rollers and the edge cutting and forming rollers, and a radius forming mechanism in advance of said edge cutting and forming rollers for bending a tapered blank to a desired shape, the improvement consisting of a pusher mechanism for moving a blank into said radius forming mechanism, said pusher mechanism including a reversible air motor, a solenoid operated two-way air valve, and means movable by said air motor including swinging fingers which are spread apart by a blank as it moves forward and then swing back by gravity behind the back edge of said blank to engage the same, and switch means for control of said valve, said switch means including a plurality of switches in series, one of said switches being closable upon engagement by said carriage to initiate forward movement of said pusher mechanism, the improvement further including a guide shoe for guiding a blank into the radius forming mechanism.

8. In a straight line machine for fabricating tapered sheet metal blanks including a starting platform having guide means for a sheet metal blank thereon, a set of forming rollers forward of said platform for making a medial groove in said blank, a movable carriage, a saddle on said carriage for support of a sheet metal blank, cam tracks on said carriage, a set of edge cutting and forming rollers in advance of said platform, means for moving said carriage forward past the medial groove forming rollers and the edge cutting and forming rollers, and a radius forming mechanism in advance of said edge cutting and forming rollers for bending a tapered blank to a desired shape, the improvement consisting of a pusher mechanism for moving a blank into said radius forming mechanism, said pusher mechanism including a reversible air motor, a solenoid operated two-way air valve, and means movable by said air motor including swinging fingers which are spread apart by a blank as it moves forward and then swing back by gravity behind the back edge of said blank to engage the same, and switch means for control of said valve, said switch means including a plurality of switches in series, one of said switches being closable upon engagement by said carriage to initiate forward movement of said pusher mechanism, the improvement further including a guide shoe for guiding a blank into the radius forming mechanism, wherein said guide shoe includes a tapered finger for engagement with said medial groove in said blank.

9. In a straight line machine for fabricating tapered sheet metal blanks including a starting platform having guide means for a sheet metal blank thereon, a set of forming rollers forward of said platform for making a medial groove in said blank, a movable carriage, a saddle on said carriage for support of a sheet metal blank, cam tracks on said carriage, a set of edge cutting and forming rollers in advance of said platform, means for moving said carriage forward past the medial groove forming rollers and the edge cutting and forming rollers, and a

radius forming mechanism in advance of said edge cutting and forming rollers for bending a tapered blank to a desired shape, the improvement consisting of a pusher mechanism for moving a blank into said radius forming mechanism, said pusher mechanism including a reversible air motor, a solenoid operated two-way air valve, and means movable by said air motor including swinging fingers which are spread apart by a blank as it moves forward and then swing back by gravity behind the back edge of said blank to engage the same, and switch means for control of said valve, said switch means including a plurality of switches in series, one of said switches being closable upon engagement by said carriage to initiate forward movement of said pusher mechanism, said radius forming mechanism including pull rollers, curve forming rollers, and shim means for adjusting the setting of the curve forming rollers to vary the degree of curvature of a blank.
